A. KONOFF

ADJUSTABLE MOUNTING FOR ARTIFICIAL EYES

Filed March 19, 1924

Inventor

Alexander Konooff

By his Attorney

L. S. for Alexander

UNITED STATES PATENT OFFICE.

ALEXANDER KONOFF, OF NEW YORK, N. Y.

ADJUSTABLE MOUNTING FOR ARTIFICIAL EYES.

Application filed March 19, 1924. Serial No. 700,371.

To all whom it may concern:

Be it known that I, ALEXANDER KONOFF, a citizen of the United States, residing in New York city, in the county of New York and State of New York, have invented certain new and useful Improvements in Adjustable Mountings for Artificial Eyes, of which the following is a specification.

This invention relates to an adjustable 10 mounting for artificial eyes such as are used in the manufacture of dolls and the like, and an object of the invention is to devise an improved means whereby the eyeballs are rendered capable of being adjusted about different pivots and whereby, except in adjustment of the eyeballs toward and away from each other the spherical center of the balls will remain unchanged.

A more detailed object is to provide an 20 eyeball structure and means of attaching the same upon a supporting rod, which structure provides a plurality of pivot elements so designed that the eyeball may be swung with respect to the rod but without changing the 25 position of the spherical center of the ball, said structure also providing a clamp engagement of the ball upon the rod of a character enabling the ball to be adjusted at will longitudinally along the rod.

30 A further object is to so arrange the parts of the structure that they may be of simple and inexpensive design and so that they may be easily and inexpensively assembled, and so that the necessary adjustments of the eyeballs with respect to their supporting rod for thereby bringing them into proper register with the eye openings, in a manner now well known in this art, may be very easily effected.

40 Other objects and aims of the invention, more or less specific than those referred to above, will be in part obvious and in part pointed out in the course of the following description of the elements, combinations, 45 arrangements of parts and applications of principles, constituting the invention, and the scope of protection contemplated will be indicated in the appended claims.

50 In the accompanying drawings which are to be taken as a part of this specification, and in which I have shown merely a preferred form of embodiment of the invention:—

55 Figure 1 is a vertical sectional view through a doll's head illustrating the use of eyeballs and supporting means therefor con-

structed in accordance with this invention.

Figure 2 is a transverse sectional view taken upon the plane of line II—II of Fig. 1.

Figure 3 is an enlarged detail sectional 60 view through one of the eyeballs, said section being taken substantially upon the plane of III—III of Fig. 1, and

Figure 4 is a similarly enlarged sectional 65 view taken upon the plane of IV—IV of Fig. 3.

Referring to the drawings for describing in detail the structure illustrated therein the reference character L indicates a bracket which is made rigid with a part of the doll's 70 head G and which serves as a pivotal mounting for the eyeball supporting shaft H in the usual manner, said shaft having fixed thereto a weighted lever 1 by means of which the shaft will be oscillated back and forth 75 when the doll is moved from an upright to a reclining position.

Upon the rod H is mounted the two eyeballs AA which are intended to oscillate with said rod and which must therefor at all 80 times maintain a properly fitting and co-operating relation with the eyeball sockets 2 and 3 of the doll's head.

It has been found a practical impossibility to make doll heads so that the eyeball 85 sockets thereof are always of uniform size and position, and on this account it is required that the eyeball be properly adjusted when being attached into the head, and in making this adjustment the eyeballs must 90 be moved in various directions, not only longitudinally along the rod H, but also rotatably upon said rod and upon an axis extending transversally of the rod. In making these adjustments it is a matter of considerable 95 desirability that once the position of the balls longitudinally of the rod has been determined this position shall not be altered when making further adjustments, and on this account it is essential that the mentioned further adjustments shall be made about an axis which passes through the spherical center of the ball and which center lies in the central axial line of the rod H.

In order to accomplish this purpose the 105 structure herein illustrated comprehends the making of the eyeball to include a hollow semi-spherical shell 4 the outer surface of which is painted, printed, or otherwise treated to appear as an eyeball. Within this shell 110 is a clamp member 5 having a spherical outer surface portion 6 of proper shape and

proportions to fit snugly to the interior spherical surface of the shell 4. This clamp member provides spaced wall parts 7 and 8 having bearing notches 9 therein for receiving the rod H and said walls being arranged so that the notches 9 thereof are disposed at opposite sides of the spherical center 10 of the shell and in such relation that when said rod is resting in said notches then the central axial line thereof will pass through the spherical center of the sphere defined by the outer surface 6 of the clamp member, and consequently through the spherical center of the shell 4.

15 In order to hold the shell 4 and clamp member 5 in the relation indicated a second clamp member or strut 11 is provided arranged to extend across the opposite or rear side of the rod and having its opposite end portions as 12 disposed to interengage with ledge parts 13 formed upon the shell.

20 A suitable clamp screw 14 is threaded through the strut 11 and has its inner or forward end bearing against the rod so that tightening of said screw will tend to force the strut and the shell rearwardly and to force the rod and clamp member 5 forwardly thus at once holding the surface 6 of the clamp member in tight frictional engagement with the inner surface of the shell and holding the structure as an entirety firmly upon the rod.

25 The shell, clamp member, and strut, are all preferably formed as thin sheet metal stampings and the ledges 13 of the shell are therefore preferably formed as bent over extensions of the material of the shell. The forwardly facing edges of these extensions which are engaged by the end portions 12 of the strut are shaped to provide seats 15 into which the ends of the strut engage, said ends being suitably reduced and rounded so as to pivot in said seats, and said parts being shaped and disposed so that the pivotal axis defined thereby will intersect the spherical center of the shell. Suitable notches 16 are provided at diametrically opposite points in the shell 4 to permit passage of the rod H and said notches are made sufficiently large 30 to provide for considerable movement of the shell about the pivot defined by the seats 15.

35 It should be pointed out that all of the parts referred to are sufficiently flexible and that they are so constructed that even though the screw 14 be screwed down sufficiently tight to hold the eyeball against any chance of unintentional movement relative to the rod yet by the application of such finger power as may be readily applied from within the doll's head during the time while the eyeballs are being set and adjusted the parts 40 may be readily moved with respect to their different pivots. If the eyeballs require adjustment to prevent the appearance of converging or diverging sight lines this is ac-

complished by swinging one or both of the eyeballs about the pivots in seats 15, while if the eyeballs require adjustment to bring their sight lines to a common horizontal plane, or if they require adjustment to bring this common horizontal sight line to a different radial position upon the rod so as to correctly accomplish the appearance of wakefulness or sleep when the doll is moved from erect to reclining position, this is accomplished by rotating one or both of the eyeballs about the rod. Any adjustments intermediate those mentioned may be accomplished by moving one or both of the eyeballs simultaneously upon both of the mentioned pivots. And all of these adjustments amount to merely rotating the eyeballs about their spherical centers and thus occasion no displacement of the eyeballs with respect to their previously adjusted location centrally of the eyeball sockets 2 and 3.

Having thus described my invention, what I claim as new and desire to secure by Letters Patent is:

1. An adjustable mounting for a doll's eyeball comprising parts providing a plurality of separate pivots by which the eyeball is supported and upon which the eyeball is adjustable about the spherical center of the eyeball and about axes which are at an angle to each other, and manually operable means to hold the eyeball in any position to which it is adjusted about said pivots.

2. An adjustable mounting for doll's eyeballs, comprising the usual supporting rod upon which the spherical eyeballs are longitudinally adjustably mounted, each of the eyeballs comprising a spherical shell, a clamp member arranged within said shell having a spherical outer surface portion to fit the spherical inner surface portion of the shell and having a seat to receive said rod to serve thereby as a pivot to enable rotary adjustment of the shell about the axial center line of the rod, a strut connected with the shell and engaging the rod to hold the shell and clamp member connected with the rod, and said strut having pivot connection with the shell to enable rotary adjustment of the shell about an axis intersecting the axial center line of the rod.

3. An adjustable mounting for doll's eyeballs, comprising the usual supporting rod upon which the spherical eyeballs are longitudinally adjustably mounted, each of the eyeballs comprising a spherical shell, a clamp member arranged within said shell having a spherical outer surface portion to fit the spherical inner surface portion of the shell and having a seat to receive said rod to serve thereby as a pivot to enable rotary adjustment of the shell about the axial center line of the rod, a strut connected with the shell and engaging the rod to hold the shell and clamp member connected with the rod, and

said strut having pivot connection with the shell to enable rotary adjustment of the shell about an axis extending in a direction transversally of the axial center line of the rod.

4. An adjustable mounting for doll's eyeballs, comprising the usual supporting rod upon which the spherical eyeballs are longitudinally adjustably mounted, each of the 10 eyeballs comprising a spherical shell, a clamp member arranged within said shell having a spherical outer surface portion to fit the spherical inner surface portion of the shell and having a seat to receive said rod to serve 15 thereby as a pivot to enable rotary adjustment of the shell about the axial center line of the rod, and means connected with the shell and engaging the rod, adapted to hold said clamp member clamped against the shell 20 and to hold said shell and clamp member connected with the rod.

5. An adjustable mounting for doll's eyeballs, comprising the usual supporting rod upon which the spherical eyeballs are longitudinally adjustably mounted, each of the 25 eyeballs comprising a spherical shell, a clamp member arranged within said shell having a spherical outer surface portion to fit the spherical inner surface portion of the shell 30 and having a seat to receive said rod to serve thereby as a pivot to enable rotary adjustment of the shell about the axial center line of the rod, a strut connected with the shell extending across the opposite side of 35 the rod, and a clamp screw carried by said strut adjustable to press against the rod and to thereby hold said clamp member pressed against the shell and to hold said clamp member and shell connected with the rod.

6. An adjustable mounting for doll's eyeballs comprising the usual supporting rod upon which the spherical eyeballs are mounted, each eyeball comprising a spherical shell, arranged at the forward side of said 40 rod a clamp member arranged within said

shell having a seat therein which engages against the forward side of the rod to thereby serve as a pivot to enable rotary adjustment of the shell about the axial center line of the rod, said clamp member being extended to the shell for thereby holding the shell with its axial center substantially in the axial center line of the rod, bearing seats provided by the shell above and below the rod, and a second clamp member engaging the rod from behind and having pivot parts 55 engaging within the seats of the shell whereby to provide pivotal connection of the shell and the rod upon an axis extending transversally of the rod.

7. An adjustable mounting for doll's eyeballs comprising the usual supporting rod upon which the eyeballs are mounted, each eyeball comprising a semi-spherical shell arranged at the forward side of the rod, and having rear marginal parts bent forwardly and shaped to define bearing seats above and below the rod, means arranged within said shell pivotally engaging the rod and serving to hold the shell so that the spherical center 70 of the shell lies substantially in the axial center line of the rod and so that an axial line extending common to said seats substantially intersects the axial center line of the rod, and a clamp member engaging said 75 rod from behind and having pivot parts engaging within said seats.

8. Means to adjustably connect a doll's eyeball to its carrying rod comprising a plurality of separate parts adjustable as a 80 unit with respect to the eyeball to effect adjustment of the eyeball upon the rod and adjustable with respect to each other to hold the eyeball in any position into which it is moved, said parts including a pair of members movable relative to each other and means to so move said members and hold them in retaining position.

In testimony whereof I affix my signature.
ALEXANDER KONOFF.
